(57) CLAIM

The ornamental design for a bulb light strip, as shown and described.

DESCRIPTION

FIG. 1 is a front, right and top perspective view of a bulb light strip showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines in the figures illustrate portions of the bulb light strip that form no part of the claimed design. The bulb light strip is shown with a symbolic break in its length. The appearance of any portion of the article between the break lines forms no part of the claimed design.
